To all whom it may concern:

Be it known that I, Alfonso Iannelli, a citizen of the United States, residing at Park Ridge, in the county of Cook and State of Illinois, have invented a new, original, and ornamental Design for a Confessional Booth or the like, of which the following is a specification, reference being had to the accompanying drawings, forming part thereof.

Fig. 1 is a perspective view of a confessional
booth or the like, showing my new design;

Fig. 2 is a top plan view;
Fig. 3 is a side elevational view;
Fig. 4 is a front elevational view; and
Fig. 5 is a bottom plan view thereof.
I claim:

The ornamental design for a confessional booth
or the like, as shown.

ALFONSO IANNELLI.
